UNITED STATES PATENT OFFICE.

CHARLES H. HORTON, OF PAINESVILLE, OHIO.

BRICK-MACHINE.

1,210,317.

Specification of Letters Patent. Patented Dec. 26, 1916.

Original application filed March 19, 1915, Serial No. 15,347. Divided and this application filed December 23, 1915. Serial No. 68,408.

To all whom it may concern:

Be it known that I, CHARLES H. HORTON, a citizen of the United States, residing at Painesville, in the county of Lake and 5 State of Ohio, have invented new and useful Improvements in Brick-Machines, of which the following is a specification.

This application is a division of my pending application for patent on brick machines, Serial No. 15,347, filed March 19, 10 1915.

This invention relates to improvements in brick machines and more particularly to the mud press of a brick machine, the invention proposing a novel mechanism for controlling the operation of the press plates or equivalent elements of the mud press.

The pressure developed by the mud press should be carefully regulated, since it must 20 not be so great as to force the clay through the vents in the bottom of the mold or to cause the bricks to stick in or adhere to the walls of the molds, yet it must be sufficiently great to insure that the molds are 25 completely filled and that there are no voids at their corners.

The principal object of the invention is to provide mechanism for regulating or controlling the operation of a mud press where- 30 by the above requirements will be satisfied.

Further objects of the invention are to provide mud press operating mechanism of such character that the press plates or equivalent elements are operated with precision and certainty and with uniform speed and pressure developing effect.

An embodiment of the invention is illus- trated in the accompanying drawings, wherein:—

40 Figure 1 is a side elevation of a mechanism in which the features of the invention are incorporated; Fig. 2 is a detail elevation of the same in a plane at right angles to the plane of Fig. 1; Fig. 3 is a detail 45 vertical sectional view thereof; Fig. 4 is a detail plan view thereof; Fig. 5 is a detail horizontal sectional view thereof on the line 5—5 of Fig. 3; Fig. 6 is a detail view, partly in elevation and partly in section, showing 50 the press plates and die of one form of mud press in connection with which the invention may be practised.

Similar characters of reference designate corresponding parts throughout the several 55 views.

The invention is shown in the drawings as applied to a mud press of the type disclosed in my prior Patent No. 497,322 of May 16, 1893, but as regards the features of regulating the pressure developed and 60 of operatively connecting and disconnecting the reciprocatory operating element of the mud press and the driver for said reciprocatory element, it may, without changes in the salient principles of construction and 65 operation, be adapted for other types of mud or brick presses. The particular mud press disclosed includes a pair of press plates 1 mounted on parallel rock shafts 2 and 70 coöperating with a spring-pressed die 3 under or against which the molds 4 are held. The press plates 1 are moved downward and toward one another to charge the molds and are thereafter moved upward and away 75 from one another to their normal or start- 75 ing positions in which they are substantially vertically disposed.

The rock shafts 2 are operated by a reciprocatory bar 5 through a toggle system comprising links 6 fast on the rock shaft 2 80 and links 7 connecting the links 6 and the bar 5 and supporting the latter under cer- 85 tain conditions. The bar 5 derives its reciprocatory motion from the movement of a sliding head 8 operated through a connect- 85 ing link 9 from a crank arm 10 provided on an operating shaft 11.

In the embodiment shown, the regulation of the action of the mud press is had by so constructing and relating the bar 5 and the 90 head 8 that the downward movement of said bar to effect an operation of the press plates 1 may be initiated at any desired period of the movement of said head and, hence, the range of downward movement of said bar 95 from a fixed starting point may be regulated as desired. In the preferred construction disclosed, the sliding head 8 is of box-like construction, being open at its rear side, and is fitted over or partially incloses the bar 100 5. Along its rear edges the head 8 is pro- 105 vided with guide flanges 12 which engage in vertical guide-ways 13 provided at the sides of a plate 14 secured to the frame of the machine. The head 8 is also provided 105 near its rear edges with inwardly project- 110 ing guide flanges 15 which engage in grooves 16 formed in the sides of the bar 5 through an extent equal to the full length of the stroke through which the head 8 moves.

The head 8 has arranged within its lower portion a clamping shoe 17 which is operative to frictionally engage the front face of the bar 5 and to thereby cause said bar 5 to participate in the movement of said head. For the purpose of controlling the operation of the shoe 17, a horizontal rock shaft 18 is journaled in the lower portion of the head 8 and is provided with an arm 19 which 10 works in a recess 20 formed in the shoe 17. The shaft 18 projects at its ends beyond the head 8 and at one end carries a weight 21 which establishes the frictional engagement of said shoe with the front face of the bar 5.

15 The plate 14 carries at one side thereof a vertically adjustable rail 22 having a cam-faced lower end 23. The rail 22 is adjustable lengthwise of the plate 14 and is movable at any desired position along said 20 plate by means of a handle 24, being fixed at any desired position to which it is set by a pawl 25 conveniently carried by said handle and arranged to engage teeth 26 formed at the rear side of the plate 14. The 25 rail 22 coats with an arm 27 mounted upon the end of the shaft 18 opposite to that which carries the weight 21. When the free end of the arm 27, which is preferably provided with a friction roller, rides along the 30 surface of the plate 14, the weight 21 is effective to frictionally engage the shoe 17 with the front face of the bar 5 whereby said bar will participate in the movement of the sliding head 8, but when the arm 27 moves 35 along the rail 22, the shoe 17 is positively held out of engagement with the bar 5 and, hence, said bar does not participate in the movement of the head 8.

It is necessary that the press plates 1 40 should commence their operative movement from positions in which they are fully open, *i. e.*, substantially vertical positions; and to insure this result, the bar 5, regardless of its range of movement and the consequent 45 extent of movement of the press plates, must always commence its downward movement from a fixed point. This result would be defeated in case there were any uncompensated slippage (due, for example, to the 50 pressure of the clay) between the bar 5 and the head 8 on the upward or return movement of said head; and to compensate for any slippage which may occur between these parts, the upper end of the head 8 55 is formed to engage an over-hanging shoulder 30 provided on the bar 5 and thereby, on its upward movement, to positively return the bar 5 to the fixed position from which its downward operative movement is commenced.

60

The extent of movement of the bar 5, and therewith of the press plates 1, will obviously be greater or less as the rail 22 is set in a higher or lower position; but the starting positions of said bar and of said 70 press plates will be invariable, as explained, and, hence, will not be affected by adjustments of the position of the rail 22. It is obvious that by varying the extent of movement of the press plates 1, the pressure developed by the mud press may be exactly 75 regulated as conditions may require.

It is preferred to construct the shoe 17 with an engaging part 28 having a wedge fit against the body of said shoe and adjustable to vary the friction with which the shoe engages the bar 5 by a suitable screw 29 connecting the fixed and adjustable parts of the shoe.

Having fully described my invention, I 85 claim—

1. In a brick machine, in combination, a mud press, a reciprocatory bar for effecting the operation thereof, a reciprocatory head having a sliding fit on and working in parallel relation to said bar, an internally arranged clamp carried by said head for engagement with said bar at a period of the movement of said head, a weighted rock shaft for operating said clamp, an arm projecting from said rock shaft, and a member adjustable in the direction of the movement of said head for engaging said arm and thereby operating the clamp to release said bar. 90

2. In a brick machine, in combination, a mud press, a reciprocatory bar for effecting the operation thereof, a reciprocatory head having a sliding fit on said bar and provided with an internally arranged clamp for engagement with said bar at a period of the movement of said head, and means adjustable in either direction of movement of said head for controlling the operation of said clamp during periods of movement of said head, said bar having a shoulder above and overhanging said head for engagement thereby in order that said head may positively return said bar to an invariable normal position. 105

3. In a brick machine, in combination, a mud press, a pair of fixed vertical guideways, a reciprocatory head having a sliding fit in said guideways, a reciprocatory bar extending through said head and having a sliding fit therein, said bar effecting the operation of said mud press, an internally arranged clamp carried by said head for engagement with said bar at a period of the movement of said head, and means adjustable in either direction of movement of said head for controlling the operation of said clamp during periods of movement of said head. 110

4. In a brick machine, in combination, a 115

mud press having a rock shaft for effecting the operation thereof, a reciprocatory head, fixed guides for said head, a reciprocatory bar extending through said head and having 5 a sliding fit therein, toggle links connecting said bar at its upper end and said rock shaft, an internally arranged clamp carried by said head for engagement with said bar at a period of the movement of said head, 10 and means adjustable in either direction of

movement of said head for controlling the operation of said clamp during periods of the movement of said head.

In testimony whereof I have hereunto set my hand in presence of two subscribing 15 witnesses.

CHARLES H. HORTON.
